ATTORNEY.

UNITED STATES PATENT OFFICE.

HENRY A. WAHLERT, OF ST. LOUIS, MISSOURI, ASSIGNOR TO THE ACME PIPE CLAMP COMPANY, OF ILLINOIS.

DESIGN FOR A PIPE-CLAMP.

SPECIFICATION forming part of Design No. 30,442, dated March 28, 1899.

Application filed September 14, 1897. Serial No. 651,689. Term of patent 14 years.

To all whom it may concern:

Be it known that I, HENRY A. WAHLERT, a citizen of the United States, residing at St. Louis, in the State of Missouri, have invented and produced a new and original Design for Pipe-Clamps, of which the following, taken in connection with the accompanying drawing, is a full and exact description.

The drawing illustrates in perspective a pipe-clamp having a form or configuration which embodies my design.

The design relates to pipe-clamps composed of two members A and B, the member A having the form of an arch or U, as at a, with lateral recessed flanges a', while the section B has the rectangular concave-faced central portion b, of a width equal to the inner lines or base of the arch or U shaped portion of

member A, and laterally-projecting straight flanges b', whose contour corresponds with the recesses in the flanges a' of the member A, said members A and B taken together having the form of an arch with central circular opening and projecting laterally at the base, which configuration constitutes the essential feature of my design.

Having thus particularly pointed out the shape or configuration of my design, I claim—

The design for a pipe-clamp as herein shown and described.

In testimony whereof I hereunto attach my signature in the presence of two witnesses.

HENRY A. WAHLERT.

Witnesses:

JNO. R. WILLIAMS,
C. C. ZIEGLER.
